UNITED STATES PATENT OFFICE.

WLADYSLAW P. KLOBUKOWSKI, OF WARSAW, RUSSIA.

HEATER.

1,107,966.

Specification of Letters Patent.

Patented Aug. 18, 1914.

Application filed July 7, 1910. Serial No. 570,801.

To all whom it may concern:

Be it known that I, WLADYSLAW P. KLOBUKOWSKI, a subject of the Czar of Russia, and a resident of Warsaw, Poland, Russia, have invented certain Improvements in Heaters, of which the following is a specification.

One object of my invention is to provide a novel form of hot air heater which will 10 efficiently transfer the heat of the products of combustion to the air to be used in heating, without at any time exposing said air to such a high temperature as to burn or decompose the dust or other organic solids 15 or gases carried thereby; the arrangement of parts being such that all contact of the air with surfaces at abnormally high temperature is avoided.

Another object of the invention is to 20 provide a heater with a novel arrangement of conduits for gradually and completely transmitting the heat from the products of combustion to the air to be heated; the invention also contemplating a novel construction whereby heated air is delivered 25 into the fire pot or combustion chamber of the heater so as to insure the complete combustion of gaseous material and solid particles driven off from the fuel in order to effectually prevent the production of smoke.

I further desire to provide a heater of the above noted general character with improved means for supplying moisture to the heated air in direct proportion to the quantity and temperature of said air; the arrangement being such as to most efficiently 35 perform the various functions above noted while at the same time being compact and substantial in construction.

These objects and other advantageous ends I secure as hereinafter set forth, reference being had to the accompanying drawings, in which:—

Figure 1, is a vertical section illustrating the preferred arrangement and construction of my improved heater; Figs. 2, 3, 4, and 5 are respectively horizontal sections taken on the lines *a—a*, *b—b*, *c—c*, and *d—d*, of Fig. 1; Fig. 6 is a fragmentary vertical section of a portion of the preferred form of humidifier employed as part of my heater; Fig. 7, is a fragmentary plan of the humidifier shown in Fig. 6, and Fig. 8 is a fragmentary perspective view illustrating 55 in detail certain features of my invention.

In the above drawings, 1 represents a

supporting structure of any suitable form having passages 2 for the supply of cold air to the heater and so placed as to open into the bottom outside parts of the main heater casing which is preferably formed of two walls 3 and 3^a of sheet metal, made one within the other; but separated so as to have between them a thin body of dead air for insulating purposes. Within the center of the casing is mounted the heater proper which consists of a fire pot 4 having a grate 5, an ash pit 6, and a combustion chamber 7 above the fire pot from which a number of smoke pipes 8 lead upwardly through a horizontally placed, ring-shaped collecting pipe 9 to a single pipe 10 connected to a stack. It is to be noted that the fire pot is made in a number of independently removable sections 4^a, one vertical edge of each of which is designed to fit into a suitably formed recess in the adjacent edge of another section. These sections are partly kept in place by one of the edges of the tube 14 which fits into an annular recess formed in the top edges of said fire pot sections, and partly by an annular shoulder on the top of the ash pit structure. By this construction it is possible to very easily remove and replace any part of the fire pot which may at any time be injured or burnt out by the intense heat; the various joints being preferably made gas tight by means of asbestos or other suitable cement.

Surrounding the fire pot and ash pit, but spaced away from the walls of the same, is an inclosing casing 11 so arranged that the space between it and said ash pit and fire box walls connects at the bottom with a horizontal flue or air box 12 leading through the main heater casing to the front of the furnace, where it is provided with a door 3^c having one or more dampers.

As shown in Figs. 3 and 4, certain portions of this space inside of the casing 11 is divided by vertical partitions to form conduits 13 communicating with the annular tube 14 as shown particularly at the left-hand side of Fig. 1, said tube being removably mounted immediately above the fuel-containing portions of the fire pot, and provided with a series of openings 15 whereby air may be discharged into the interior of the fire pot and combustion chamber. Other conduits, 13^a, formed by the aforesaid vertical partitions, the fire-pot 4 and the casing, 11, open into the space, 17, defined or in-

closed by the plate, 19, the outer wall of the combustion chamber, 7, and a cover plate, 18, there being two sets of conduits, 20 and 21, each having their upper ends connecting 5 with the space, 17, and thence extending downwardly therefrom, one of the sets of conduits, 20, having its lower end leading into the ash-pit, 6; the other set of conduits, 21, having their lower ends connecting with 10 the air-box or conduit, 12, located beneath the ash-pit, as shown in Fig. 1. It will thus be seen that one set of conduits, 20, enters the top of the ash-pit, 6, while the other set of conduits, 21, enters the air-box or conduit, 12. Said conduits, 20 and 21, as shown 15 in Figs. 3 and 4, may be ordinary pipes 10^a, of circular cross section suitably incased, though they preferably have a corrugated or other form of extended surface in order to 20 facilitate the rapid transfer of heat through their walls. Hot air pipes 22 lead from the top of the main heater casing to any desired distributing system for the hot air, and with this arrangement of parts, when fuel is burnt 25 in the fire pot 4, the heat therefrom is transferred to the cold air delivered from the openings 2 in such a manner that any organic material carried by said air is not burnt or exposed to such a high temperature 30 as will decompose any of its constituents.

Suitable doors, not shown, are provided for the ash pit and fire box, although the first of these is preferably kept closed except when it is desired to remove ashes. 35 A greater or less amount of air is delivered into the conduit or air-box 12 through its door or through the dampers therein, and of this air a portion rises within the conduits 13^a which communicate with the air box 12 40 and enters the space 17 after passing the highly heated walls of the fire pot and combustion chamber, thus becoming heated to a high temperature. From this space it passes down through the conduits 20 and 21, flowing 45 from the first of these to the ash pit 6 and thence through the grate, thus materially aiding in the combustion of the fuel. The remainder of the heated air from the space 17 passes through the conduits 21 into 50 the conduit or air box 12, whence, as before described, a portion of it, with a certain proportion of fresh cold air, passes up through the conduits 13^a. The second part of the air from the conduit or box 12 passes up 55 through the conduits 13 alongside of the fire pot 4 and from thence enters the annular and highly heated conduit 14; being delivered through the openings 15 thereof immediately above the surface of said fuel in 60 said fire pot. This highly heated air so far aids in the combustion of the gases driven off from the fuel as to cause these to be completely burnt, likewise causing complete burning of the solid particles of fuel, thereby 65 most effectually preventing smoke and

materially adding to the efficiency of the heater.

The cold air passing up from the conduits 2 into the space within the main heater casing necessarily flows around the extensive surface 70 presented by the conduits 20 and 21 as well as over the outside surface of the casing 11, the pipes 8 and the cover 18. While all of these surfaces are heated, their temperature is not sufficiently high to decompose or injuriously affect any of the organic constituents of the air; the proportioning of the conduits 8 being such that their parts exposed to this air are at a moderate temperature such as to insure the desired results. 75 Owing to the large surface thus presented, the air within the main heater casing is thoroughly and rapidly heated to the desired temperature and passes out through the pipes 22. By means of a damper 23 of any 80 suitable form, the flow of air into the conduits 13 may be regulated at will.

In order to supply moisture to the air in sufficient amounts to secure the best hygienic conditions, I provide a sectional annular humidifier 25 preferably mounted upon horizontal portions of the conduits 20 surrounding and immediately adjacent to the casing 11. As shown in Figs. 6 and 7, said humidifier preferably consists of a narrow, 90 relatively deep, annular container 25 whose outer wall is less in height than its inner wall, which has surrounding it a series of concentric channels 25^a, 25^b, etc., arranged in stepped form and having through it a 95 number of openings 26 for the passage of air. If desired, an overflow opening 28 may be arranged from the lowermost of these channels to carry off the surplus water. In order to increase the rate of evaporation of 100 the water from this device, without adjusting it, I may mount in the container 25 an annular body of fire brick or other relatively porous material; preferably forming this in a series of sections and flanging it outwardly as shown at 29, so that under operating conditions liquid drawn up into it by capillary action is thoroughly exposed to the action of the rising currents of air. By reason of the fact that this humidifying device is mounted around and immediately adjacent to the casing 11 or directly around the fire pot if the casing should be omitted, the liquid within it is heated to an extent 110 in a great degree proportional to the temperature of the fire pot and to the rate at which fuel is burned in the heater, so that the amount of liquid evaporated bears a definite relation to the volume of air which 115 is heated. Thus when the heater is driven to its full capacity, the air delivered therefrom is more highly heated and passes through it in greater quantities than when it is burning less fuel, and the amount of 120 moisture supplied by the air is automatically 125 increased. The humidifier 25 is connected 130

cally regulated, being at all times supplied in the desired and necessary amounts.

By the above arrangement of parts, the combustion may be very accurately controlled by the regulation of the amount of air delivered to the box or conduit 12 and also by the amount supplied therefrom to the tube 14; it being possible at all times to prevent the escape of smoke from the combustion chamber to the stack since the supply of hot air immediately above the surface of the fuel causes all smoke as well as gases to be completely burnt. Above all, the air to be heated is not at any time allowed to strike highly heated surfaces, being delivered from the heater at the desired temperature and in the best condition from a hygienic standpoint, since it is free from the various de-composition products otherwise present.

It is to be noted that the casing 11 and its associated parts may, without departing from my invention, be applied to other forms of heaters in order to prevent the contact of the air, used in heating, with the intensely heated metal surfaces of the fire pot, combustion chamber, etc.

While I have described and illustrated the container constituting the hopper as formed in a number of steps, it is obvious that the angle and detail arrangement of these may be varied within wide limits without departing from my invention; the object of which is to provide a water container immediately adjacent the sides of the fire pot.

It is of course immaterial as to whether the source of heat with which my invention is used be a fire pot in which fuel is burnt, a steam or water radiator, or an electric heater, since in any case there is the certainty that air to be heated will be exposed to contact with metallic surfaces at a high temperature. My invention therefore contemplates any form of heater in which an initial source of heat is spaced away from a structure having a heat radiating surface, in combination with the necessary conduits or structures for circulating some heat transferring medium such as air between the source of heat and the said structure and the necessary conduits for causing the air to be heated to pass over and adjacent the heat radiating surface.

I claim;

1. The combination in a heater, of a casing having a fire-pot, an ash-pit, and an air-box; sets of conduits in the casing, certain of the conduits of one set having both ends connected to the air-box, and the conduits of another set having one end connected to said air-box and the other end connected to the ash-pit; and means for supplying air to and receiving it from the space surrounding said sets of conduits.

2. The combination in a heater, of a cas-

ing having a fire-pot, an ash-pit, and an air-box; sets of conduits in the casing, certain of the conduits of one set having both ends connected to the air-box and the conduits of another of said sets having one end connected to said air-box and the other end connected to the ash-pit, the conduits of a third set surrounding the fire-pot and having openings thereinto above the fuel level thereof and being connected to said air-box; and means for supplying air to and receiving it from the space around said sets of conduits.

3. The combination in a heater of a casing having a fire-pot, an ash-pit and a combustion chamber above the fire-pot; a second casing inside the first casing inclosing the ash-pit and fire-pot, said second casing having vertical partitions forming a set of conduits surrounding the fire-pot; a box under the ash-pit connected with the lower portions of said set of conduits and adapted to connect with a source of air supply; other conduits connecting the upper portion of said set of conduits with said box; and means for supplying air to and receiving it from said casing.

4. The combination in a heater of a casing; an ash pit, a fire pot, and a combustion chamber therein; a second casing inside of the first casing inclosing the ash pit and fire pot and provided with vertical partitions forming a set of conduits adjacent the fire pot; a box under the ash pit connected with said set of conduits and in communication with a source of air supply; two sets of conduits respectively connecting the upper portions of said first set of conduits with said box and with the ash pit; with conduits for supplying air to and receiving it from said casing.

5. The combination in a heater of a casing; a fire pot therein having a set of vertical conduits adjacent its outside surface, of which certain open into the fire pot; a box connected to all of said conduits and in communication with a source of air supply; and conduits connecting the upper portions of others of said set of conduits with said box; with conduits for supplying air to and receiving it from said casing.

6. The combination in a heater of a casing; a fire pot and an ash pit therein; a set of vertical conduits adjacent the outside surface of said fire pot, of which certain open into the fire pot; a box connected to said conduits and connected to a source of air supply; two sets of conduits connected to the upper portions of others of said first set of conduits; certain of said second-named conduits being connected to said box and others being connected to the ash pit; with conduits for supplying air to and receiving it from said casing.

7. The combination in a heater of a main

- 4
- outside casing; a fire pot and an ash pit in the casing; a second casing surrounding said fire pot; a structure within the main casing inclosing a portion of said second casing; 5 said structure including conduits connecting the upper end of the space between the fire pot and the second casing with the ash pit; with conduits for supplying air to and receiving it from said main casing.
- 10 8. The combination in a heater of a main outside casing; a fire pot, an ash pit, and an air box in said main casing; a second casing; a structure extending around a portion of the second casing within the main casing 15 and including a set of conduits of which certain connect the space between the fire pot and the second casing with the ash pit, and others connect said space with the air box; with conduits for supplying air to and receiving it from said main casing respectively.
- 15 9. In a heater, the combination with a casing, a fire-pot, an ash-pit, and an air-box, of conduits within the casing surrounding the fire-pot and connecting with the air-box 20 and adapted to circulate an initial body of air, means for passing a second body of air in contact with the conduits conveying the initial body of heated air whereby the circulating heated air gives off a portion of its 25 heat to the second body of air, said conduits arranged to discharge the circulating air into the fire-pot to promote combustion of fuel, and means for conducting the second-named body of air to the place to be heated. 30
- 35 In testimony whereof, I have signed my name to this specification, in the presence of two subscribing witnesses.
- WLADYSLAW P. KLOBUKOWSKI.
